DESIGN FOR A PULL TOY OR SIMILAR ARTICLE

Jane F. Griffith, New York, N. Y.

Application April 4, 1946, Serial No. 128,280

Term of patent 3½ years

(Cl. D34—15)

To all whom it may concern:

Be it known that I, Jane F. Griffith, a citizen of the United States, residing at New York, in the county of New York and State of New York, have invented a new, original, and ornamental Design for a Pull Toy or Similar Article, of which the following is a specification, reference being had to the accompanying drawing, forming part thereof.

In the drawing:

Fig. 1 is a side view of a pull toy showing my new design;

Fig. 2 is a front view; and

Fig. 3 is a rear view thereof.

I claim:

The ornamental design for a pull toy or similar article, substantially as shown.

JANE F. GRIFFITH.
